UNITED STATES PATENT OFFICE.

LEROY M. LEWIS, OF PHILADELPHIA, PENNSYLVANIA, ASSIGNOR TO OWEN B. LEWIS, OF BALTIMORE, MARYLAND.

FUSIBLE LINK AND STRUT.

1,379,195.

Specification of Letters Patent. Patented May 24, 1921.

Application filed March 26, 1920. Serial No. 368,888.

To all whom it may concern:

Be it known that I, LEROY M. LEWIS, a citizen of the United States, and a resident of the city of Philadelphia, county of Philadelphia, and State of Pennsylvania, have invented certain new and useful Improvements in Fusible Links and Struts, of which the following is a specification, reference being had to the accompanying drawing, forming a part hereof.

My invention relates to fusible links and struts of the type used in fire extinguishing systems, fire doors, fire alarms and other and similar devices wherein it is desired to hold certain parts of the mechanism, to which the links or struts are applied, in assembled relation until sufficient heat is present in the vicinity of the contrivance to cause the link or strut components to become separated by the fusing or melting of the fusible material normally uniting the component parts together.

My invention relates more particularly to a new and useful means adjunctive to links and struts of the type above mentioned and which will indicate from mere inspection the completeness and the operativeness of the link or strut.

Among the objects of my invention is to provide a construction of the character mentioned whereby the link or strut may be quickly and efficiently thrown apart immediately upon the fusing of the fusible binding substance.

Another object is to so construct a device that the component parts will be normally restrained from relative movement by the use of a rigid strain or restraining member which, upon fusing of the binding material, acts to separate the component parts in a lateral direction, but which normally acts to prevent any creeping or "cold-flow" action that would interfere with the proper functioning of the device.

A further object is to provide means to prevent the misplacement or even the separation of the parts during the assembling thereof and to therefore insure against the premature operation of the device by reason of incorrect or inaccurate assembly of said parts.

A still further object is to also provide means which is of utility to indicate upon inspection the presence of an essential part

of the assembly and hence the operativeness of the device.

Other objects of my invention will more fully appear from the following specification and in the accompanying drawing.

In prior structures it has been found that links or struts of the type mentioned frequently fall or operate prematurely, usually from the fact that in assembling the parts the workman at the factory permits an essential element, such as a key, strain member or the like, interposed between the plates, to slide or fall out from therebetween and fills the space or socket, provided for such member, with solder or fusible material, the solder usually protruding more or less from the edges of the plates and from the ends of the key socket. It will be apparent that under such conditions there is nothing to indicate whether or not the key is contained within the socket, and consequently an omission of the key or strain element will render the link or strut useless. Such device may be subjected to all the careful and proper inspections desired yet inasmuch as the fusible material completely fills and hides the spaces that should be occupied by the key or similar element, it is usually assumed that the key is present and is covered by said fusible material, the defective link or strut thus passing inspection without any detection of its actual defect.

If, on the other hand, the key be properly assembled in place within the socket provided between or in the plates, it frequently occurs that the solder or fusible material is improperly applied in respect to the key and plates so that it does not effectively seal the ends of the socket at the ends of the key and it is accordingly possible, at any time, for the key to become separated from the plates without it being observed, whereupon when the link or strut is attached to a sprinkler head it will not be able to withstand the strains placed upon it by the water pressure in the system, and consequently will prematurely operate, a condition which is very annoying and objectionable as well as causing considerable damage to goods with which the water comes in contact.

Moreover it has been discovered, even though a link or strut of the type mentioned be completely assembled and properly mounted in a sprinkler head, the fusible ma-

terial at the ends of the socket may become detached or fall out by the vibrations of the pipes, such as, "water-hammers" "chattering" and the like, whereby the key may be 5 come gradually displaced and finally separated from the rest of the link or strut structure, the solder between the plates temporarily retaining the plates in unseparated condition but soon resulting in a premature 10 operation of the sprinkler head.

My invention, therefore, involves the idea of constructing the fusible link or strut with means adapted to avoid the conditions mentioned above and which will respond only 15 in the presence of heat sufficient to fuse the fusible material and to properly operate at the time and in the manner in which it is intended. I accomplish this by making the 20 key socket of the closed type whereby the key is entirely inclosed or nested within the socket space provided between or within deflected or offset portions of the link or strut plates.

One of the important features of my invention is to provide the key or strain member 25 with visible projecting indicators which are readily perceived from the exterior of the link or strut structure and which act as a positive indicator of the completeness of 30 the structure. The underwriters now require that all structures of the type mentioned above should be provided with means indicating that the link or strut is complete and that no essential element thereof may 35 be absent or the fact of its absence be hidden from view in the manner above indicated in the previous structures.

To this end my invention consists of the features of novelty that I hereinafter describe with reference to the accompanying 40 drawings forming a part hereof and in which;

Figure 1 is a view in side elevation of a link constructed in accordance with my invention,

Figs. 2 and 3 are respectively vertical sectional and side elevational views of the link shown in Fig. 1,

Figs. 4 and 5 are respectively top plan and 50 side elevational views of the key or strain member included in the link structure shown in Figs. 1, 2 and 3,

Figs. 6 and 7 are views respectively in elevation and longitudinal section of another 55 form of link structure,

Figs. 8 and 9 are similar views of still another form,

Figs. 10 and 11 are similar views of a still further form, and,

Fig. 12 is a sectional view of a further construction.

The link or strut forming the subject-matter of the present invention embodies in the main three elements, to wit, two preferably substantially flat members or plates

adapted to be connected together by their adjacent faces with fusible material or solder and a pressure sustaining or restraining member or key interposed between said plates and acting to normally prevent relative movement of said plates until the fusible material has become sufficiently fused to permit said key to operate to separate said plates. In one of the forms, however, three plates are used but the assembly and the 75 functioning thereof is analogous to the structures provided with merely two plates as will appear more fully hereinafter.

As illustrated, my improved links and struts comprise, in the preferred form shown in Figs. 1 to 5 inclusive, a pair of substantially rectangular flat plates 1 and 2 each respectively provided near one end thereof with the apertures 3 and 4 and at the other end thereof with notches 5 and 6. These plates are adapted to be placed together face to face and with the apertured end of one adjacent the notched end of the other, so that the apertured ends extend in opposite directions with the aperture of one plate registering with the notch of the other plate. The apertures 3 and 4 are adapted to receive the parts to be connected to the link when the latter is assembled for operation, such as the projecting lever arms of the 85 members of a two-part toggle type of strut or lever arrangement frequently used in 90 sprinkler heads.

The plates 1 and 2 may be provided with laterally bent or deflected portions 7 and 8 which form therebetween a substantially rectangular form of socket of a length less than the width of the plates, with a shoulder or support 9 formed on the plate 1 and a similar shoulder 10 formed on the plate 2. Between the laterally bent portions 7 and 8 and the shoulders 9 and 10 is located a key member 11 which is of substantially rectangular form with the exception of its central portion and is adapted to fit in the socket at a slight inclination to the planes of the plates 1 and 2 whereby as one plate moves longitudinally relatively to the other the key will be caused to rock upon the shoulders 9 and 10 to a horizontal position 105 whereby the plates will be separated from each other.

One of the plates, as for example plate 2, may be provided in the bent portion 8 thereof with an aperture 12 of any suitable form but preferably of rectangular shape. The key 11 is provided at its central portion thereof with a laterally bent or deflected portion or projection 13 of preferably angular form. This projecting portion is located in the link or strut structure so as to project through the opening 12 out of contact with or in spaced relation to the edges of said opening and extending beyond the plane of the surface 14 of the bent por- 110 115 120 125 130

tion 8 so that the ridge or external portion 15 of the bent portion 13 will protrude exteriorly of the solder 17 filled into the space provided by the opening 12, the ridge or 5 projection 15 being of utility to indicate the presence of the key within the socket of the plate assembly so that upon inspection it may be determined with certainty whether or not the link or strut structure is complete and includes the key or strain member 10 which is a very essential element in this type of device. The key is formed preferably of sheet metal by stamping out in a diepress and is first cut in substantially rectangular 15 form then centrally deflected to provide the angular projection 13 and the ridge 15 thereof. It is also found convenient to remove side portions of the projection 13 by beveling or cutting off at an angle the ends 20 thereof as clearly shown at 16 in Figs. 2, 3 and 4 of the drawing. By so shortening the length of the ridge 15 the length of the opening 12 may be accordingly made of less extent so that, as the key is caused to rock 25 upon the shoulders 8 and 9 in the socket formed between the plates, the ends of the ridge 15 will be able to clear the ends of the opening 12; thereby avoiding any possibility of interference with a proper and complete 30 operation of the link structure upon the fusing of the fusible material between the plates.

Fusible material 17 is usually located between the plates 1 and 2 as well as in the 35 free spaces included between the key and the plates in the socket formed therebetween.

It will be further observed that the socket portion formed in each plate member 1 and 2 does not extend the full width of the plates 40 but terminates at a short distance from the edges 18 and 19 of the plates 1 and 2 whereby the ends 20 and 21 of the key member will be adapted to abut against or contact with the ends 22 and 23 of the socket formed 45 between the plates, as is clearly shown in Fig. 1 of the drawing. By providing the socket with the ends 22 and 23 as shown, a longitudinal movement of the key 11 will be prevented, the same being completely housed 50 or nested between the plates and prevented from separation from the plates.

In operation the structure may be suspended upon the ends of a pair of arms of a toggle type strut so that there is a normal 55 tendency to move the plates 1 and 2 in the direction of the arrows shown in Fig. 2, the shoulders 9 and 10 bearing against the lateral edges of the strain receiving portions of the key 11. Inasmuch as the key is in inclined position to the line of strain tending 60 to move the plates 1 and 2 relatively longitudinally there is a component force tending to rock the key laterally and to force the plates 1 and 2 apart, the solder 17 being 65 sufficient to restrain this action so long as the

solder remains congealed. Upon the occurrence of a fire, the heat thereof will, at a certain temperature, cause the solder to fuse and the plates will immediately be permitted to move first longitudinally and then, by 70 reason of the rocking of the key 11 in the socket thereof, laterally, causing the plates to draw away from each other and to be thrown apart, the projection 13 on the key being withdrawn through the opening 12 75 of the plate 2 without interference therewith.

Referring to the form of structure shown in Figs. 6 and 7 I have shown therein a central plate 24 and side plates 25 and 26, the 80 latter two being substantially of the same form. The plate 24 is provided at its lower end with an opening 27 in register with notches 28 and 29 provided in the lower ends of the plates 25 and 26 respectively, while at 85 the upper end of the plates 25 and 26 are provided openings or apertures 30 and 31, respectively, in register with a notch 32 provided in the upper end of the central plate 24. The plates 25 and 26 may be provided 90 with flared portions 33 and 34 between which may be included a bearing member 35 of relatively hard material or of fusible material as desired.

The central plate is provided with a central aperture 46 and the plates 24 and 25 are provided with laterally bent socket portions 36 and 37, of substantially hemi-spherical form, so as to include therein and therebetween a ball 38 of substantially spherical 95 form. The socket portions 36 and 37 are provided with apertures 39 and 40 through which may extend visible indicating projections 41 and 42, preferably integrally formed with the ball 38 and with the ends 100 thereof projecting a suitable distance beyond the external surface of the solder 43 and 44 filled in the apertures 39 and 40, as is clearly shown in Fig. 7. Solder 45 is included between the plate members and the 110 ball in the usual manner.

In the operation of this form of device the central plate tends to move downwardly and the side plates tend to move upwardly, the upper edge of the aperture 46, bearing 115 against the ball 38 tending to move the same downwardly. As soon as the fusible material 49 melts or fuses, the ball 38 is forced downwardly relative to the plates 25 and 26 against the surfaces 47 and 48 thereby causing the plates 25 and 26 to separate laterally, the ball 38 passing downwardly between the lower ends of the plates 25 and 26 and the projections 41 and 42 being withdrawn 120 through the apertures 39 and 40. The upper end of the plates 33 and 34 may coact with the member 35 so that the latter will permit the separation of the ends 33 and 34 later than the separation of the lower ends 125 of the plates 25 and 26 whereby the mem- 130

ber 35 acts more or less like a hinge at the start of the separation of the link elements.

Referring to the structure shown in Figs. 8 and 9 the same comprises adjacently located plates 49 and 50 each provided at an end with an aperture 51 and 52 and at the opposite end with a notch 53 and 54 whereby the aperture 51 registers with the notch 54 and the aperture 52 registers with the notch 53. The plates 49 and 50 are provided at their central portions with laterally deflected portions 55 and 56 provided with preferably rectangular apertures 57 and 58. Within the socket provided between the portions 55 and 56 is located a key 59 of polyhedral form with the ends 60 and 61 thereof in the form of wedges or pyramids. The key may be provided with laterally extending indicating projections 62 and 63 extending through the apertures 57 and 58, out of contact with the edges thereof and with the ends of the projections 62 and 63 protruding beyond the outer surface of the solder 64 and 65 filled into the apertures 57 and 58 so as to be visible to the outside, as is clearly shown in Fig. 9. The plates and the key are united by fusible solder 66.

In the operation of this type of link, the plates 49 and 50 normally tend to move longitudinally relative to each other in the direction of the arrows, shown in Fig. 9, whereby the tapered ends 60 and 61 of the key operate as entering wedges between the plates, when the fusible material 66 melts, so as to cause a lateral separation of the plates. As the plates are laterally moved accordingly, the edges of the openings 57 and 58 are adapted to clear by the ends of the projections 62 and 63 provided on the key 59.

Referring to the structure shown in Figs. 10 and 11 I have shown therein a pair of plates 67 and 68 provided with socket portions 69 and 70 of substantially semi-cylindrical form adapted to include a solid cylindrical key 71 in a substantially upright position, as shown in Fig. 10. The plates 68 and 69 are provided with apertures 72 and 73 and notches 74 and 75 as in the forms described above. The socket portions 69 and 70 may be provided with apertures 76 and 77 through which normally project the visible projections 78 and 79, preferably formed integral with the key 71, the openings 76 and 77 being filled with solder 80 and 81, as shown. The plates and the key are united by solder 82.

In the operation of this device, when the solder 82 is caused to fuse, the plates 67 and 68 first move longitudinally whereupon the key 71 is caused to rock within the socket portions 69 and 70 so as to cause the plates 67 and 68 to separate laterally. During such movement the fusible projections 78

and 79 will be caused to be withdrawn through the apertures 76 and 77 respectively. The projections 78 and 79 normally project a suitable distance beyond the exterior surface of the solder 80 and 81 so as to provide visible means indicating the presence of the key within the socket.

In Fig. 12 I have shown a link utilizing a cylindrical key in substantially transverse position relative to the plates thereof, this link comprising a pair of plates 83 and 84 provided with apertures 85 and 86 and notches 87 and 88 as in the forms above described. Both plates are provided with laterally extending socket portions 89 and 90 between which is located a cylindrical key 91. The socket portions 89 and 90 are provided with apertures 92 and 93 which are preferably of rectangular form and disposed diametrically opposite each other on a line at substantially 45° to the plane of the plates 83 and 84. The key 91 is provided with laterally extending visible projections 94 and 95 extending respectively through the apertures 92 and 93 and being preferably formed integral with the cylindrical key 91, and out of contact with the edges of said openings, as is clearly shown in Fig. 12. The plates 83 and 84 and the key 91 are normally held together by fusible solder 96.

In the operation of this device, when the solder 96 fuses, the plates 83 and 84 first move longitudinally whereby the socket portions 89 and 90 will be caused to ride over the curved surface of the pin 91 and then to be laterally separated from each other, the projections 94 and 95 being withdrawn through the apertures 92 and 93 without interfering with the relative movement of the plates 83 and 84.

In the forms shown in Figs. 6 to 12 inclusive I have shown the key member provided with a pair of visible projections but it is to be understood that the use of two projections is not essential but the use of but a single projection is sufficient or, on the other hand, if desired a larger number of projections than two may be utilized. In the several embodiments disclosed the visible projection is so located through an aperture as to project substantially beyond the exterior surface of the fusible material normally filling the aperture so that the same may be visible for inspection at any time whether before or after assembly of the link or strut. The appearance of such projection will always indicate with certainty that the key member is present within the socket provided between the plates of the links structure so that no link will be assembled with merely a quantity of fusible material in the key socket space without the presence of the key or in which event the same will be readily detected by reason of the absence of the indicating projections.

While I have herein disclosed and shown upon the drawing a few embodiments of my invention it is to be understood that the latter is not limited to the particular details disclosed but that other devices, constructions and arrangements of parts may be utilized and applied in other relations without in any way departing from the spirit of my invention and the scope of the appended 10 claims.

Having thus described my invention, what I claim and desire to protect by Letters Patent of the United States is:

1. In a fusible link or strut, the combination of adjacently located plates provided with socket portions, a strain member fitting within said socket portions between said plates, said strain member having an indicating projection extending laterally 20 through an aperture provided in one of said plates, said projection being out of contact with said plates and projecting beyond the plane of the external surface of said apertured plate, and fusible material located between said plates for binding the same together and for maintaining the plates and the strain member in fixed relative position until fused by heat.

2. In a fusible link or strut, the combination of a pair of plates provided with socket portions and a strain member located in said socket portions, said strain member provided with an indicating projection extending through an aperture provided in one 35 of said socket portions, said projection being spaced from the ends of said strain member and out of contact with said plates and fusible material between said plates for binding the same together and for maintaining 40 said strain member in fixed relative position until said material is fused by heat.

3. In a fusible link or strut, the combination of a pair of adjacently located plates provided with laterally deflected socket portions and a strain member fitting within 45 said socket portions, said strain member provided with an integrally formed laterally extending indicating projection extending through and beyond an aperture provided 50 in one of said socket portions, said projection being out of contact with said plates and fusible material between said plates for binding said plates together and for holding said plates and said strain member in fixed relative position until said material is fused by heat.

4. In a fusible link or strut, the combination of a pair of plates provided with socket portions and a strain member fitting 60 into said socket portions, said strain member provided with an integrally formed laterally extending indicating projection spaced from the ends of said strain member and extending through an aperture provided in one of 65 said socket portions, said projection being

out of contact with said plates and fusible material between said plates for binding said plates together and for retaining said plates and said restraining member in fixed relative position until fused by heat.

5. In a fusible link or strut, the combination of a pair of plates provided with socket portions and a strain member fitting in said socket portions between said plates, said strain member provided with an integrally formed substantially V-shaped laterally extending indicating projection in spaced relation with respect to the ends of said strain member, and extending through an aperture provided in one of said socket portions beyond the external surface of said socket portion, said projection being out of contact with said plates and fusible material between said plates for binding said plates together and for retaining said plates and said strain member in relative position until fused by heat.

6. In a fusible link or strut, the combination of a pair of plates provided with socket portions, a strain member fitting in said socket portions between said plates, said strain member provided with an integrally formed substantially V-shaped projection spaced from the ends of said strain member and with the sides or edges of said projection tapered, said projection extending through and beyond an aperture provided in one of said socket portions and out of contact with said plates, and fusible material located between said plates for binding said plates together and for retaining said plates and said strain member in fixed relative position until fused by heat.

7. A key for fusible links and struts comprising spaced strain portions and intermediate integral formed laterally projecting V-shaped portion, said V-shaped portion having its sides and edges tapered, said tapered projecting portion being spaced from the ends of said key.

8. In a fusible link or strut, the combination of a pair of plates provided with a keyway between said plates, one of said plates provided with an aperture opposite said keyway and spaced from the lateral edges of said plates, a key in said keyway provided with a laterally bent portion extending through said opening and projecting beyond the exterior surface of the plate provided with said opening and fusible material between said plates and in said opening for binding said plates together and for retaining said plates and said key in fixed relative position until said material is fused by heat.

9. In a fusible link or strut, the combination of a pair of plates provided with a keyway between said plates, one of said plates provided with an opening intermediate the ends of said plate and keyway and opposite said keyway, a key located in said keyway

and adapted to receive the strain tending to part said plates, said key being provided with a laterally bent portion opposite said opening and extending through said opening to the exterior of the plate provided with said opening and out of contact with said plate, said projection being visible at the exterior of said plate when said aperture is filled with fusible material, and fusible material between said plates for binding said plates together and for retaining said plates and said key in relative position until said material is fused by heat.

10. In a fusible link or strut, the combination of a plurality of plates arranged in substantially parallel relation, fusible material between said plates for binding said plates together, said plates provided with apertured and socket portions for the inclusion 15 of a strain member, a strain member located in said socket portion, said strain member being provided with a laterally extending portion projecting through an aperture pro-

vided in one of said plates and extending exteriorly thereof for visibility, said laterally extending portion being located in spaced relation to and out of contact with said apertured plate, and fusible material in said aperture.

11. In a fusible link or strut, the combination of a plurality of plates normally held together with fusible material, said plates provided with socket portions intermediate the ends thereof, a strain member located in the socket formed by said socket portions, 35 said socket portions provided with apertures, said strain member provided with laterally extending projections extending through said apertures and out of contact with said plates, said apertures being filled 40 with fusible material and the ends of said projections extending exteriorly of said solder in said apertures.

In witness whereof I have hereunto set my hand this 22nd day of March, 1920.

LEROY M. LEWIS.
